(57) **CLAIM**

The ornamental design for a massage apparatus, as shown and described.

DESCRIPTION

FIG. 1 is a perspective view of a massage apparatus according to the present application;

FIG. 2 is a top view thereof;

FIG. 3 is a bottom view thereof;

FIG. 4 is a front view thereof;

FIG. 5 is a rear view thereof;

FIG. 6 is a right view thereof; and,

FIG. 7 is a left view thereof.

The broken lines shown in the figures are for the purpose of illustrating portions of the massage apparatus, which form no part of the claimed design.

1 Claim, 5 Drawing Sheets
